UNITED STATES PATENT OFFICE

HERBERT NIGEL GRESLEY, OF HADLEY WOOD, ENGLAND

LOCOMOTIVE

Application filed July 30, 1928, Serial No. 296,229, and in Great Britain May 16, 1928.

This invention relates to the tenders of locomotives, more especially tenders of railway locomotives employed for long non-stop runs and which are usually constructed so as to carry an appropriate supply of fuel or coal for the boiler furnace as well as a supply of water for feeding the boiler. On long non-stop runs it is necessary, or at all events very desirable, that a change of engine crew 10 can be made during the run and this has been impossible with the usual construction of tender.

The present invention consists principally in a locomotive tender having a passage-way 15 or corridor extending through it from end to end so that the driver and fireman on the foot-plate of the locomotive can pass therefrom through the said corridor to the front coach or vehicle,—for instance guard's van,—20 of the train, and the relief engine crew can pass from the said coach or vehicle to the foot-plate of the locomotive. A vestibule, which may be similar to the usual vestibules provided on corridor and Pullman car trains, 25 is provided on the rear end of the tender so as to provide the necessary connecting gangway between the tender and the adjacent vehicle of the train.

The floor of the above-mentioned corridor 30 is preferably located at a level above the level of the bottom or floor of the coal bunker of the tender and thus a considerable distance above the bottom of the water tank or water space of the tender so that as large a water 35 space as practicable (consistent with an appropriate height of the corridor) is provided beneath the floor of the corridor the space below the corridor being open to and forming part of the water tank or water 40 space of the tender.

Further there is comprised in or combined with the structure of the tender an appropriate weight or heavy mass at the side of the tender where the corridor is located, for the 45 purpose of compensating or making up for loss of weight at the said side due to the space taken up by the corridor.

Further features of construction of a tender according to the invention will be described hereinafter with reference to the ac-

companying drawings and set forth in the appended claims.

In the drawings Fig. 1 shows, in side elevation and more or less diagrammatically, a railway locomotive tender according to this 55 invention, Fig. 2 being a plan view of same.

Figs. 3 and 4 are respectively a front and a rear end view of the tender.

Fig. 5 is a plan, drawn to a larger scale, of a portion of the front end of the tender at and 60 adjacent to the corridor side of the tender.

Like reference numbers indicate corresponding parts in the several figures of the drawings.

1 indicates the side wall or plates of the 65 tender at the side where the corridor 2 is provided, the said plates forming the outer wall of the corridor; as shown in Fig. 2 the corridor 2 extends from the foot-plate or platform 3 at the front end of the tender to the 70 opposite or rear end at which a portion 2^a of the corridor extends transversely of the water tank or water-space at that end of the tender. 4 indicates the bottom or floor of the coal 75 bunker, 5 being the downwardly inclined end or wall of the coal bunker. As usual the coal bunker or space includes the top of the forward portion 5^a of the water tank to the right of the usual transverse partition 55, Figs. 1 and 2.

6, Figs. 1, 3 and 4 indicates the floor of the corridor 2 which, as will be seen, is located at a position well above the bottom 7 of the water space or water tank of the tender and also above the floor 4 of the coal bunker. The 85 space below the corridor floor 6 communicates with and thus forms part of the water tank space of the tender, as does also the space below the floor 4 of the coal bunker.

8 is the vestibule platform and 9 the vestibule fitted to the rear end of the tender. 10 is an opening or doorway in the rear end wall of the tender and to which the transverse part 2^a of the corridor leads, the said opening leading to the vestibule 9 which, when the tender is 95 coupled to a train, is connected in the usual or any appropriate manner with the corresponding vestibule on the adjacent vehicle of the train.

11, Fig. 2, indicates a hinged door hinged 100

to one side of the doorway 10. As shown in Fig. 2 the door 11 is arranged to open inwardly. 12, Figs. 2 and 3, is a door at the front or foot-plate end of the corridor 2, the said door being arranged to open outwardly. 13 and 14, Fig. 3, indicate the hinges of the door 12, which are mounted on any appropriate part of or attached to the tender structure.

15 and 16, Figs. 1 and 4, indicate steps leading from the floor 6 of the corridor to the lower level of the floor of the transverse part 2^a of the corridor which is on the level of the bottom 7 of the tender. These steps 15 and 16 may be formed of steel plates secured to appropriate angle irons comprised or provided in the structure of the tender.

17 and 18, Figs. 2 and 3, are steps leading from the floor 6 of the corridor to the lower level of the platform or foot-plate 3 at the front end of the tender. These steps may also be formed of plates secured to angle irons comprised or provided in the structure of the tender. In one embodiment however, as hereinafter described, the step 18 is formed 25 as part of a massive casting comprised or provided in the structure of the tender and serving to make up or compensate for loss of weight due to the space taken up by the corridor 2. This casting is indicated by the reference number 19 in Figs. 1, 2, 3 and 5, and as shown in Figs. 2, 3 and 5 the major portion of the surface of this casting is flush with and forms part of the platform or foot-plate 3 on which boarding may (as is usual) be provided for the fireman to stand on while shovelling coal from the front or outlet end of the coal bunker to the locomotive fire box. 20, Fig. 3, is the usual hinged door at the foot-plate or front end of the coal bunker, 21 being the usual space, below the said door, for insertion of the fireman's shovel.

19^a, Fig. 5, are countersunk bolt holes to accommodate bolts (not shown) by which the casting 19 is secured to appropriate angle irons or other parts of or embodied in the structure of the tender; and 19^b, 19^c are recesses formed in the casting 19 the recess 19^b being provided to accommodate the vertical shaft 19^d of the hand brake on the tender, and the recess 19^c to accommodate the nut by which the usual hand rail 99 at the front end of the tender is secured.

The inner wall 2^b of the corridor 2 is formed by plates secured by rivets or bolts (not shown) to appropriate uprights or angle irons forming part of the structure; for example, in the embodiment illustrated the plates forming the inner wall 2^b of the corridor would be secured to the outer vertical members of the angle iron frames 22, the inner inclined members of said frames 22 and of the similar frames 23 at the other side of the tender having secured to them the plates forming the sloping or inclined sides or walls 24, 25, Figs. 2 and 3, of the coal bunker, an

appropriate number of the frames 22, 23 being provided and spaced the required distance apart longitudinally of the tender. 26, Figs. 1 and 3, indicate other angle irons to which the plates of the inner wall 2^b of the corridor are riveted or otherwise secured, appropriately curved plates forming the top or roof 2^c of the corridor being also secured to the angle irons 26 the lower ends of which may be secured, for instance by rivets or bolts, to the transverse beam or angle iron 27 (Fig. 3) forming part of the tender structure. It will be understood that, as usual, an appropriate number of transverse beams similar to the angle iron 27 are embodied in the structure, as well as the required number of vertical and longitudinal angle irons. As these angle irons or beams are usual and form no part of the present invention they are not shown in the drawings.

In the embodiment illustrated plates forming the bottom or floor of the corridor 2 are secured, by rivets, or otherwise, to the under side of angle irons 28, Figs. 3 and 4, extending along the tender from end to end of the corridor 2, 2^a.

As shown in Figs. 1 and 3 the angle irons 26 have upwardly turned ends 26^a (or they may be short uprights welded on the angle irons 26) situated on or approximately on the longitudinal centre line of the roof 2^c of the corridor 2, and a rod or bar 29 (Figs. 1 and 3) is welded, riveted or otherwise secured to the said uprights 26^a forming a guard rail to prevent coal from the bunker rolling or being thrown, for instance by rocking of the tender when travelling at high speed, across the curved roof 2^c of the corridor and on to the track.

Instead of, or in addition to, the massive casting 19 serving as a balancing or compensating weight as hereinbefore-mentioned, a weight 30 may be provided along the bottom or floor 6 of the corridor. As shown in Fig. 1 this weight consists of a number of castings 30, 30^a, 30^b, 30^c of appropriate size and weight, the castings 30^a, 30^b and 30^c tapering gradually towards the rear end of the tender so that the end of the casting 30^c adjacent to the rear end of the corridor is flush or almost flush with the plates forming the floor of the corridor at the rear end thereof. The upper sides of the castings may be appropriately chequered or roughened to provide a better foothold for the engine crew walking along the corridor. The castings 30 may be secured to the structure of the corridor floor 6 in any appropriate manner, for instance by means of countersunk bolts.

Instead of the weight 30 being superimposed on the floor 6 of the corridor as above described, it may be located immediately below the said floor, or it may be located on the structure of the tender at the bottom thereof and beneath the corridor 2, the said weight

being in either of these positions located in the tank or water space which, as already mentioned, extends under the corridor 2.

As a further alternative, instead of the 5 weights or castings 19 and 30 above referred to, the plates forming the sides 1 and 2^b, bottom or floor 6, and roof 2^c of the corridor 2, and if desired also the angle irons or beams forming part of the structure, may be made 10 of greater weight than usual and thus provide weight on the corridor side of the tender to compensate for the loss of weight due to the provision of the corridor 2 in the tender.

31, Figs. 1, 3 and 4 indicates angle iron 15 frames embodied in the structure of the tender below the floor 6 of the corridor 2 and supporting the said floor.

32, Figs. 1, 2 and 4 indicates a circular 20 glazed window in the end wall of the corridor 2 at the rear end of the tender. If desired a similar window may be provided in the door 12 at the front end of the corridor 2.

As shown in Figs. 2 and 3, the coal bunker 25 is out of balance, the major coal space of the bunker lying to one side of the longitudinal central plane of the tender. In order to compensate for or counteract this unbalanced condition of the coal bunker, the hereinbefore-mentioned frames 22, at the side of the 30 coal bunker adjacent to the corridor 2, are made of less width transversely of the tender than the frames 23 at the opposite side of the tender, and the inner inclined parts or members of the said frames 22 are so formed 35 that they, and consequently the plates forming the sloping side or wall 24 (Figs. 2 and 3) of the coal bunker, have a much sharper or steeper incline than the corresponding parts or members of the frames 23 carrying 40 the plates forming the other sloping side or wall 25 of the coal bunker.

Details of construction and arrangements hereinbefore described and shown in the drawings may be modified or varied without 45 departing from the invention.

What I claim is:—

1. A locomotive tender having a corridor extending through it from end to end, said corridor being provided with a roof and sides 50 which extend upwardly to its roof, for the purposes set forth.

2. A locomotive tender having a corridor extending along one side of the tender from end to end thereof, for the purposes set forth.

55 3. A locomotive tender having a corridor extending through it from end to end and along one side, and the floor of the corridor at a higher level than that of the bottom or 60 floor of the coal bunker.

4. A locomotive tender having a corridor extending from end to end and along one side of the tender, the floor of the corridor located at a level a substantial distance above 65 the bottom of the tender, and the space below

the said floor communicating with the water tank space of the tender.

5. In a locomotive tender the combination, with a corridor extending along one side thereof from end to end of the tender, of a compensating weight at or adjacent to the side of the tender at which the corridor is located, for the purposes set forth.

70 6. A locomotive tender having combined in its structure a corridor extending along one side and from end to end of the tender, and a compensating weight consisting of a massive casting located at the forward end of the tender with the upper surface of the said casting flush with the foot-plate of the tender, 80 for the purposes set forth.

75 7. A locomotive tender having a corridor extending along one side of the tender and from end to end thereof, and a compensating weight consisting of a casting located adjacent the said corridor at the forward end of the tender, the major portion of the top surface of said casting lying flush with the foot-plate of the tender, and an upward projection of the said casting adjacent the end of 90 the corridor and forming a step leading from the floor of the corridor to the lower level of the foot-plate, for the purposes set forth.

95 8. A locomotive tender having a corridor extending through it from end to end and along one side of the tender, an aperture constituting a doorway in the rear end wall or plates of the tender, and a vestibule secured to the said rear end wall at the said aperture, for the purposes set forth.

100 9. In a locomotive tender, the combination of a corridor extending along one side of the tender from end to end thereof and transversely of the tender at its rear end, the floor of the corridor being above the bottom of the tender, steps at the rear end of the corridor floor and leading therefrom to a landing at the bottom of the tender, a doorway in the rear end wall of the tender centrally thereof and leading from the said landing, and a 110 vestibule at the said doorway and secured to the tender, for the purposes set forth.

115 10. The combination, in a locomotive tender, of a corridor extending along one side of the tender, from end to end thereof, the outer wall of the corridor consisting of the plates forming the side of the tender and the inner wall of the corridor consisting of plates supported by members comprised in the structure of the tender, a roof on the corridor the 120 said roof consisting of curved plates and projecting above the side of the tender, and an aperture in the rear end wall of the tender the said aperture forming a doorway leading to and from the rear end of the corridor, for 125 the purposes set forth.

130 11. The combination, in the structure of a locomotive tender of a corridor having outer and inner walls and extending along one side of the tender from end to end thereof, and a

coal bunker the inclined or sloping side of which, adjacent to the said corridor, is so constructed that it has a much steeper incline than the inclined side of the bunker remote from the corridor, for the purposes set forth.

5 12. A locomotive tender having a corridor extending through it from end to end, and having sides which extend upwardly to its roof, and a door for closing the corridor arranged at one end thereof.

10 13. A locomotive tender having a corridor extending through it from end to end, and having sides which extend upwardly to its roof, and doors arranged at each end of the corridor for closing it.

15 In testimony whereof I affix my signature.
HERBERT NIGEL GRESLEY.
